OPPOSED PISTON TWO-CYCLE ENGINE

Hans Vonrütli, Winterthur, Switzerland, assignor
to Schweizerische Lokomotiv-und Maschinen-
fabrik, Winterthur, SwitzerlandApplication May 13, 1944, Serial No. 535,478
In Switzerland April 8, 1943

8 Claims. (Cl. 123—51)

This invention relates to two-stroke internal-combustion engines in which two opposed pistons work in each cylinder and the pistons act by the intermediary of links on rocking levers mounted on the fixed engine casing. The object of the invention is the provision of an internal-combustion engine of the aforesaid type which occupies a reduced space and is of relatively small weight, while it affords easy accessibility of all parts, particularly of the pistons.

According to the invention four or more working cylinders are disposed substantially in a plane extending at right angles to the crank shaft, the axes of the cylinders being tangential to at least one circle which is concentric to the axis of the single crank shaft receiving the power of all the pistons.

The accompanying drawing represents by way of example a preferred embodiment of the invention.

Fig. 1 shows the internal-combustion engine, partly drawn in longitudinal section through the cylinders, and partly in elevation.

Fig. 2 is a plan view drawn in section according to the line II—II of Fig. 1.

The pairs of pistons 1 and 2, 3 and 4, 5 and 6, 7 and 8 work as opposed pistons in the cylinders 9, 10, 11 and 12, each one of the four cylinders comprising one pair of opposed pistons. The axes of successive cylinders are disposed at right angles one relatively to the other and extend tangentially with respect to a circle 20 having its centre in the axis 21 of the crank shaft and situated in a plane which is perpendicular to this axis. The axes of the cylinders form together with their points of intersection a regular rectangle or a square. When the cooperating pistons are in their innermost position, as for example the pistons 1 and 2 in Fig. 1, the compression space is enclosed between these two pistons and the cylinder wall; when the pistons are at their outer extreme positions, as for example the pistons 3 and 4 in the cylinder 10, scavenging is effected through the series of ports 13, 14 and the annular ducts 15, 16. Air enters through one of the two port series, for example, ports 13 and leaves the cylinder through the other series 14. The scavenging pump is diagrammatically represented in the drawing by a centrifugal turbo-blower 60 and can be driven by an exhaust gas turbine 61. However, it will be understood that the particular means for providing scavenging and charging air is of no importance so far as the present invention is concerned.

Links 17 are hingedly connected with one end to 55

the pistons 1 to 8. Each two pistons, as the pistons 2 and 3, working in cylinders the ends of which are adjacent and face each other and forming a right angle one with another, are hingedly connected by means of the links 17 to the outer arm of a common rocking lever 18. The rocking lever 18 associated with the pistons 2 and 3 has its hub 22 pivotally mounted on a pin 24 secured to the casing 23 and carries on its inner end a pin 25, on which the connecting rod 26 is hingedly mounted. The head 27 of the connecting rod is engaged on a crank pin 28 of the crank shaft 30.

The outer ends of the rocking levers are forked, the fork portions 31 being so spaced that after 15 removal of the pins 32 connecting the link 17 to the rocking lever 18, the respective link together with the piston can be withdrawn from the cylinder without the rocking lever interfering with such removal. At the outer ends of the rocking 20 levers, removable covers 33 are provided for the purposes of withdrawal of the pistons. The pins 32 can be dismounted after removal of the lateral covers 46.

While the rocking lever 18 is associated with 25 the pistons 2 and 3, and connected to the crank pin 28 by means of the connecting rod 26, the rocking lever 34 associated with the pistons 6 and 7, has its inner arm connected to the crank pin 36 by means of the connecting rod 35, this crank 30 pin 36 being displaced through 180° with respect to the pin 28. The rocking levers 39 and 40, indicated in dash and dot lines only in Fig. 1 and associated with the pistons 8, 1 and 4, 5, respectively, act by means of connecting rods 41 and 42, 35 respectively on the crank pins 43 and 44. Obviously, the inner ends of the rocking levers 39 and 40 are situated in the same plane perpendicular to the crank shaft 30 as the corresponding crank pins 43 and 44; the inner end of the rocking lever 39 is represented in dash and dot lines 40 in Fig. 2 in substantially the position in which it arrives during the scavenging period in the cylinder 9.

The flange 45 of the crank shaft may be connected with a fly wheel. In addition to the series 45 of cylinders 9 to 12, there can be provided a second series of four cylinders also disposed in a plane perpendicular to the crank shaft axis, which second series would be placed axially behind the cylinders 9 to 12 in Fig. 1 and positioned in the same manner as these latter; two cylinders 51 and 52 of this second series of cylinders are represented in plan view in Fig. 2. In order to connect the pistons of these cylinders to the corresponding rocking levers, the hubs 22 of the

Links 17 are hingedly connected with one end to 55

levers are provided with additional forks 31a, as represented in Fig. 2 for the rocking levers 18 and 34.

Instead of providing only four cylinders, the engine can comprise five, six or more cylinders disposed in the same plane. In this case the axes of the cylinders form a polygon which can be regular or irregular. It will, however, be recognized, that the utilization of the transmission linkage will be most effective when providing an even number of cylinders, although it will be possible, as mentioned, to construct the internal combustion engine according to the invention with an uneven number of cylinders. Preferably the series of cylinders are so disposed that one corner of the polygon formed by the cylinder axes is downwardly directed, or that this corner is situated vertically beneath the centre of the polygon. In this case all injection nozzles placed in the middle of the cylinders are easily accessible. When however the polygon is so situated that one side thereof extends horizontally and forms the base of the polygon, then all the pistons are readily accessible.

It is to be understood that the above disclosed structure is merely illustrative and that various changes and modifications may be made in the practice of my invention without departing from the scope of the appended claims. 25

I claim:

1. A two-stroke internal-combustion engine of the opposed piston type comprising at least four cylinders substantially disposed in the same plane, two opposed pistons working in each cylinder, a single crank-shaft means connecting the pistons of all cylinders with said crank shaft, said crank shaft extending at right angles to the plane of the cylinders, and the axes of the cylinders being tangential to a circle disposed coaxially with the crank shaft.

2. A two-stroke internal-combustion engine of the opposed piston type comprising at least four cylinders substantially disposed in a single plane, two opposed pistons working in each cylinder, a single crank shaft extending at right angles to the plane of the cylinders, and means operatively connecting the pistons of all cylinders to said crank shaft, the axes of the cylinders being tangential to a circle disposed coaxially with the crank shaft, said axes forming with their points of intersection a regular polygon having the axis of the crank shaft passing through the center thereof.

3. A two-stroke internal-combustion engine of the opposed piston type comprising a plurality of series of at least four cylinders, the different series of cylinders being substantially disposed in single parallel planes, two opposed pistons working in each cylinder, a single crank shaft extending at right angles to said parallel planes of the cylinders, and means operatively connecting the pistons of all series of cylinders to said crank shaft, the axes of the cylinders of each series being tangential to a circle disposed in the respective plane of the cylinders and coaxially with the crank shaft.

4. A two-stroke internal-combustion engine of the opposed piston type comprising at least four cylinders substantially disposed in a single plane, two opposed pistons working in each cylinder, a single crank shaft means including connecting rods connecting the pistons of all cylinders with said crank shaft, said crank shaft extending at

right angles to the plane of the cylinders, the cylinders having their axes disposed tangentially to a circle whose center lies in the axis of the crank shaft, and a common rocking lever operatively connected to two pistons of the opposite ends of each two successive cylinders and to the crank shaft for transmitting the forces of said pistons to the crank shaft.

5. A two-stroke internal-combustion engine of the opposed piston type comprising at least one series of at least four cylinders disposed in a single plane, two opposed pistons working in each cylinder, a single crank shaft extending at right angles to said plane of the cylinders, the cylinders having their axes disposed tangentially to a circle whose center lies in the axis of the crank shaft, and the axes of two successive cylinders intersecting at an angle of at least 90°, a common rocking lever operatively connected to two pistons working in opposite sides of each two successive cylinders, and a connecting rod disposed between each rocking lever and the crank shaft to transmit the forces of said two pistons to the crank shaft.

6. A two-stroke internal-combustion engine of the opposed piston type comprising at least four cylinders disposed in a single plane, two opposed pistons working in each cylinder, a single crank shaft extending at right angles to said plane of

30 the cylinders, said cylinders having their axes disposed tangentially to a circle whose center lies in the axis of the crank shaft, rocking levers for transmitting the forces of the pistons to the crank shaft, a link connecting each piston to a rocking lever, 35 said rocking levers having a forked end, and a pin carried by the forked end of the rocking levers to hingeably connect said link to the lever, the two branches of the forked end of the rocking levers being so spaced that after withdrawal of 40 said pin the pistons can be removed from the cylinders without the rocking levers interfering with such removal.

45 7. A two-stroke internal-combustion engine of the opposed piston type comprising at least four cylinders disposed in a single plane, two opposed pistons working in each cylinder, and a single crank shaft extending at right angles to said plane of the cylinders, said cylinders having their axes disposed tangentially to a circle whose center lies in the axis of the crank shaft whereby the axes of the cylinders with their points of intersection form a polygon, and the cylinders being disposed in a vertical plane and in such relation 50 with respect to said circle that one corner of said polygon is situated vertically below the center of the polygon.

60 8. A two-stroke internal-combustion engine of the opposed piston type comprising at least four cylinders disposed in a single plane, two opposed pistons working in each cylinder, a single crank shaft extending at right angles to said plane of the cylinders, and means operatively connecting the pistons of all cylinders to the crank shaft, said cylinders having their axes disposed tangentially to a circle whose center lies in the axis of the crank shaft whereby the axes of the cylinders with their points of intersection form a polygon, and the cylinders being disposed in a vertical plane and in such relation with respect to said circle that one side of said polygon extends horizontally as base of the polygon.

HANS VONRÜTL.
